Chrysler Corporation, Highland Park, Mich., a corpora-
tion of Delaware

Filed June 27, 1962, Ser. No. 70,714

Term of patent 7 years

(Cl. D14—30)

FIG. 1.

FIG. 2.

FIG. 3.

FIG. 1 is a front elevational view of an automobile wheel cover showing my new design;

FIG. 2 is a sectional view taken on the line 2—2 of FIG. 1; and

FIG. 3 is a fragmentary enlarged sectional view of the portion of the automobile wheel cover indicated by a broken line 3 in FIG. 2.

The dominant features of my design reside in the full line portions of the drawing.

I claim:

The ornamental design for an automobile wheel cover substantially as shown and described.
